UNITED STATES PATENT OFFICE.

FRANK W. MERRICK, OF BOSTON, MASSACHUSETTS, ASSIGNEE TO UNION LOCK STITCH COMPANY, OF BOSTON, MASSACHUSETTS, A CORPORATION OF MAINE.

THREAD-CONTROLLING MECHANISM FOR SEWING-MACHINES.

1,129,827.

Specification of Letters Patent.

Patented Feb. 23, 1915.

Original application filed September 19, 1910, Serial No. 582,599. Divided and this application filed November 20, 1911. Serial No. 661,372.

To all whom it may concern:

Be it known that I, FRANK W. MERRICK, a citizen of the United States, residing at Boston, in the county of Suffolk, State of Massachusetts, have invented a certain new and useful Improvement in Thread-Controlling Mechanism for Sewing-Machines, of which the following is a specification, reference being had therein to the accompanying drawings.

The invention has relation to the devices which are employed in hook-needle sewing machines for controlling the thread which is supplied to the needle.

The invention provides in improved manner for the support and actuation of the thread-guide which lays the thread around the needle and into the open eye of the latter, and for the support and actuation of the thread-finger or thread-hook which draws out the length of thread which is to be pulled by the needle through the material being stitched in making the next stitch. The general objects in these connections are to simplify and improve the general construction of the machine, and to secure increased stability and durability. The machine is better adapted for high speed on different classes of work, and freedom from wear and breakages is attained.

An embodiment of the various features of the invention is illustrated in the accompanying drawings, in which latter,—

Figure 1 shows in side elevation certain of the parts of a curved-needle sewing machine having the said embodiment applied in connection therewith, the take-up arm being partly broken away. Fig. 2 shows some of the said parts in plan. Fig. 3 shows the needle and awl and the actuating mechanism therefor, omitted from Figs. 1 and 2.

The present invention is a division of that forming the subject of my original application for U. S. patent for improvements in thread-controlling mechanism for sewing machines, filed Sept. 19, 1910, Serial No. 582,599.

Having reference to the drawings,—the machine-frame is marked 1, and 2 is the main or driving shaft.

At 3 is the work-support, and 4 is the presser between which and the work-support the work *a* to be stitched is placed. The presser-carrier is omitted.

In Figs. 1 and 3 15 is a curved awl, and 16 the awl-carrier segment, 17 being a curved hook-needle and 18 the needle-carrier segment. The two carrier-segments are mounted to turn around a common center, and are connected to swing in unison by means of a pin 19 (shown by dotted lines) carried by one carrier-segment and passing transversely through a hole in the other carrier-segment. They are actuated from the main or driving shaft 2 through connections including a link 21, of which only a portion is shown in Fig. 1, having one end thereof connected pivotally to an arm 20 projecting from one carrier-segment. The said link is connected pivotally at its other end to an arm 22, Fig. 3, of the transversely-extending rockshaft 22^a mounted in the machine-frame. A second arm of the said rockshaft is connected by means of a pitman or connecting rod 23 to a crank 24 with which the main shaft 2 is furnished. As the shaft 2 rotates, the two carrier-segments and the awl and needle mounted thereon are oscillated.

Referring, now, to the thread-guide by which the thread is laid around the needle and into the open eye of the latter, it is shown at 25, Figs. 1 and 2. It is secured to a carrier-lever 26. I construct the said carrier-lever with an open hub-portion, 85 shown best in Fig. 1, which encircles loosely a collar 27, Fig. 2, that is sleeved loosely upon the transversely-extending horizontal needle-and-awl actuating rockshaft 22^a. The said hub-portion is swiveled to the said collar by means of upper and lower center-screws 28, 28. As thus mounted, the thread-guide carrier-lever is capable of swinging transversely in the direction of the length of the rockshaft upon its pivotal connection 90 with the collar, while in addition the carrier-lever and collar are capable of oscillating around the rockshaft. For the actuation of the carrier-lever and thread-guide a cam 29 is fixed upon the shaft 2, such cam having a cam-groove receiving a cam-follower 26^a which is connected with the rear arm of the carrier-lever. The said cam-groove has radial throws acting to oscillate the carrier-lever and thread-guide vertically, and also lateral throws acting to swing the carrier-lever and thread-guide transversely, so as thereby to cause the thread-guide to

travel in the required path to lay the thread in the eye of the needle. In practice, a spring, 26^b, acts upon carrier-lever 26 with a tendency to press the cam-follower 26^a toward the bottom of the cam-groove.

At 30 is the thread-finger or thread-hook by means of which the length of thread to be drawn through material *a* by the needle in the descent of the needle is extended in 10 a bend or bight. It is secured to a carrier-lever 31 which is mounted upon rockshaft 22^a alongside the collar 27 with capacity to turn loosely on the said rockshaft, and is actuated by means of an edge-cam 32 on 15 shaft 2, which engages with a cam-follower 31^a carried by the rear arm of the carrier-lever 31. In practice, a spring, 31^b, acts upon the carrier-lever 31 with a tendency to press the cam-follower 31^a against the edge 20 of the cam 32.

The employment of the needle-and-awl actuating rockshaft 22^a as a support for the carrier-levers of the thread-guide and thread-finger or thread-hook provides effectively for 25 the secure mounting of the said carrier-levers in the proper relative positions with respect to the other working parts to obtain advantageously the coöperation of the thread-guide and thread-finger or thread-hook with 30 the needle, slack-thread controller, and take-up, and dispenses with separate studs or pivots. The general construction of the machine is simplified and improved, and 35 durability and freedom from wear and breakages are secured.

The needle-thread, as it extends from the source of supply, passes down into the wax-pot 33, then up to and through a tension-device 34, then to the locking device, then to 40 the take-up, and thence past a slack-thread controller and through the thread-guide 25 to the work *a*.

The take-up consists of a vibrating arm 45 carrying two thread-engaging rolls 36, 36, and a coöperating thread-engaging roll 37 which is mounted on a pivot 38 upon the head-portion of the machine-frame 1, the said roll 37 engaging with the thread at a 50 point intermediate the points at which the two rolls 36, 36, engage therewith. The arm 35 is fixed upon one end of a rockshaft 39 extending through a sleeve bearing 40 in connection with the said head-portion of the machine frame, as shown best in Fig. 2. 55 The said rockshaft has fixed upon its other end a second arm, marked 41, carrying a cam-follower 42 working in the cam-groove 43 of a cam-wheel 44 fixed on shaft 2. As 60 the said cam-wheel rotates, it communicates a vibrating movement to the take-up arm, as a result of which the rolls 36, 36, on said arm coöperate with the fixedly mounted roll 37, and with the grip-device, to draw out the thread in extended bends or bights at opposite sides of the roll 37, thereby taking up 65

the thread between the grip-device and the work in completing each stitch as it is formed.

The slack-thread controller is located between the take-up device and the thread-guide. It comprises a fixed plate or rest 45 for the thread, and a movable plate or pressure-member 46 carried by a lever 47 which is pivoted at 48 to the fixed head-portion of the machine-frame, the said lever having 70 engaged therewith one end of a contracting spiral spring 49 having the other end thereof connected with the said head-portion. The thread passes between the pressure-member 46 and the rest or backing 45, and is subjected 75 to pressure between them, due to the action of the spring 49 in tending to turn the lever 47. The slack-thread controller is so disposed that the portion of thread passing therethrough draws in nearly a straight line 80 between the adjacent roll 36 of the thread-guide and the thread-passage of the thread-guide 25. It acts to hold back the portion of thread which is slackened by the giving-up action of the take-up, after the taking-up action has occurred, but permits the thread to pass forward under sufficient control to the stitch-forming devices as needed 85 in the formation of a new stitch.

The thread-lock comprises a lever 50 and 90 a bearing or rest 51 for the thread. The said lever is pivoted at 52 upon the head-portion of the machine-frame adjacent the take-up arm, and in such relation to the latter that the thread on its way from the 95 tension device 34 engages with the lever before reaching the first of the moving take-up rolls 36. The lever 50 is furnished with a laterally-extending thread-gripping stud or projection 50^a, which is carried by one arm 100 of the lever adjacent the pivot of the latter, the said stud or projection being arranged to co-act with the backing or rest 51 in gripping the thread at the required times. The said backing or rest is constituted by a 105 fixed stud or projection carried by the support of the grip-lever. The thread passes between the backing or rest and the stud or projection 50^a of the lever. The long arm 110 of the lever has at its forward end a guide 115 which engages with the thread intermediate the gripping surfaces and the first roll 36 of the take-up device, the said guide being at a somewhat greater distance from the pivot of the lever than the gripping stud 120 or projection 50^a. When the taking-up action of the take-up device begins, the pull of the thread upon this arm of the lever acts with sufficient leverage and force to turn the lever around its pivotal center so 125 as to pinch the thread by means of stud or projection 50^a against backing or rest 51. When the pull of the take-up upon the thread relaxes, the pressure of the said stud or projection is also relaxed, and the grip 130

upon the thread ceases. The action in this respect is as usual.

I have shown herein means adapted to be brought into action by the operator to suspend the locking of the thread while a taking-up action occurs, but have not described the same, inasmuch as it forms no part of the present invention and is claimed in the original application hereinbefore 10 mentioned.

I claim as my invention:—

1. In a hook-needle sewing machine the combination with needle-actuating mechanism including a transversely-extending 15 horizontal rockshaft, of a collar sleeved loosely on said rockshaft, a carrier-lever pivotally connected to the collar and provided with a thread-guide, and actuating connections for said carrier-lever by which it is swung transversely with relation to the collar and the carrier-lever and collar are oscillated bodily around the rockshaft and the thread guide thereby caused to lay the thread in the open eye of the needle.
2. In a hook-needle sewing machine the combination with needle-actuating mechanism including a transversely-extending horizontal rockshaft, of a collar sleeved loosely on said rockshaft, a carrier-lever 20 having an open hub-portion encircling said collar and pivotally engaged therewith at opposite points, and provided with a thread-guide, and actuating connections for said carrier-lever by which it is swung transversely with relation to the collar and the carrier-lever and collar are oscillated bodily around the rockshaft and the thread guide thereby caused to lay the thread in the open eye of the needle.
3. In a hook-needle sewing machine the combination with needle-actuating mechanism including a transversely-extending horizontal rockshaft, of a collar sleeved loosely on said rockshaft, a carrier-lever 25 provided with a thread-guide, oppositely located center-screws by which the carrier-lever is pivotally engaged with the collar, and actuating connections for said carrier-lever by which it is swung transversely with relation to the collar and the carrier-lever and collar are oscillated bodily around the rockshaft and the thread guide thereby caused to lay the thread in the open eye of the needle.

3. In a hook-needle sewing machine the combination with needle-actuating mechanism including a transversely-extending horizontal rockshaft, of a collar sleeved loosely on said rockshaft, a carrier-lever 40 provided with a thread-guide, oppositely located center-screws by which the carrier-lever is pivotally engaged with the collar, and actuating connections for said carrier-lever by which it is swung transversely with relation to the collar and the carrier-lever and collar are oscillated bodily around the rockshaft and the thread guide thereby caused to lay the thread in the open eye of the needle.

4. In a hook-needle sewing machine the combination with needle-actuating mechanism including a rockshaft, of a collar sleeved loosely on said rockshaft, a carrier-lever provided with a thread-guide and pivotally engaged with said sleeve with 50 capacity for transverse movement, means for swinging said carrier-lever transversely and rocking the carrier-lever and sleeve bodily to thereby cause the thread-guide to travel in the required path to lay the thread 55 in the open eye of the needle, a carrier-lever mounted upon the said rockshaft alongside said collar and provided with a thread-measuring finger, and means to oscillate the latter carrier-lever around the said rockshaft.

In testimony whereof I affix my signature in presence of two witnesses.

FRANK W. MERRICK.
